UNITED STATES PATENT OFFICE.

RICHARD HARGRAVE, OF JACKSONVILLE, FLORIDA.

DESIGN FOR AN ELECTRIC SIGN.

49,962.

Specification for Design.

Patented Nov. 28, 1916.

Application filed October 2, 1915. Serial No. 53,850. Term of patent 7 years.

To all whom it may concern:

Be it known that I, RICHARD HARGRAVE, a citizen of the United States, residing at Jacksonville, in the county of Duval and State of Florida, have invented a new, original, and ornamental Design for Electric Signs, of which the following is a specification, reference being had to the accompanying drawing, forming part thereof.

The figure is a front elevation of the electric sign, showing my new design.

I claim:

The ornamental design for an electric sign, as shown.

RICHARD HARGRAVE.

Witnesses:

JAMES H. BUNCH,
C. R. BENTON.
